JOSEPH W. FAY, OF MILWAUKEE, WISCONSIN.

JAR CLOSURE.

Application filed May 12, 1921. Serial No. 468,974.

The invention relates to the metallic screw caps or covers used to seal the open mouths of fruit jars or other jars, which are usually made of glass, and of which the well-known 5 Mason jar, provided with screw threads about its neck for engagement by the cap, is a conspicuously familiar type.

Screw caps for Mason jars are spun or stamped from zinc plates, which material is 10 well adapted for use in the formation of a cap for a fruit jar, for the reason that such metal is not subject to corrosive attacks by the acids contained in the various fruits when the latter are placed in the jars and 15 sealed by the application of the caps thereto.

The extreme ductility of the metal referred to also constitutes a characteristic which has rendered it peculiarly adaptable for the purposes mentioned, in that it admits of ready formation into the desired shapes. But the said metal is likewise pliable in a very great degree; so much so, in fact, that it is necessary to provide the cap with a lining which will resist the expansive 25 pressure of the gases sometimes generated by the contents of the sealed jars. The lining intervenes to prevent the outward distortion of the top of the cap by the internal pressure, which is sustained by the lining. 30 Thus, through the agency of the lining, the top of the cap remains flat, and bulging thereof is avoided. The lining is formed as a disc of vitreous material, and is of sufficient thickness to enable it to withstand 35 the expansive pressure referred to.

Although the lining, as well as the cap, is not subject to the action of the acids contained in the contents of the jar, the assemblage of the lining within the cap is such 40 that it is impossible to exclude germs from lodging in the spaces between the assembled parts. In such hidden location, the germs are inaccessible and are not susceptible to being dislodged in the ordinary sterilizing 45 operations to which the cap is subjected after its removal from the jar. As a result of this unhygienic condition, the germs greatly multiply, but remain undisturbed and when the cap is again used to cover a 50 filled jar, the germs attack the contents and fermentation ensues. This condition is responsible for most of the difficulty experienced by housekeepers in having their canned goods spoil.

The vitreous lining of the cap contributes 55 nothing toward the preservation of the contents of the jar. The lining possesses only the function ascribed, namely, that of relieving the metal cap of the expansive pressure generated within the jar. Its presence, 60 however, creates a situation which frequently is attended with serious disappointment as well as loss, in that it affords concealment for germs which later bring about the destruction of the canned fruit. 65

In one of its aspects, my invention is embodied in a cap made of zinc, as usual, so that it will not be subject to attack by the acids contained in the contents of the sealed jars, and from which cap the vitreous 70 lining heretofore employed, is omitted. This omission leaves the inside of the cap entirely clear and free from crevices or spaces within which germs might find a hiding place, and so escape destruction when the 75 caps are subjected to the sterilizing operation which later follows the opening of the jar.

The absence from my improved cap of the lining which subserves only the useful purpose of maintaining the top of the zinc cap in its flat or plane state, is compensated for by the provision of an exteriorly located reinforcement for the cap, which serves to maintain the top of the latter in the desired planular condition. This reinforcement may be constructed of any suitable metal, selected with particular regard to its possession of rigidity in a degree which will be sufficient 80 to enable it to withstand the expansive pressure before referred to, and at the same time possess ductility to an extent which will permit it being easily shaped for ready application to the jar cover to which it is to be attached upon the outside thereof, so as to 85 form a permanent part of the structure.

In addition to the objections pointed out as inhering in a jar cap provided with a vitreous lining, as described, a further objection to a cap provided with such a lining resides in the fact the lining is greatly liable to fracture, and such fracture frequently occurs, when the cap is accidentally dropped to the floor. This fracture renders the cap 95 unserviceable, and the whole must be discarded. Inasmuch as the proportionate cost of the lined cap exceeds that of the jar, when 100 replacement becomes necessary, a continuing 105

expense is involved in the use of zinc caps lined with vitreous material. The replacement cost of caps by reason of broken linings, is entirely obviated by the use of my 5 invention.

As is well known by all who have used Mason jars, and other jars provided with a closure constituted as a screw cap, it is often quite difficult to remove the cap from the 10 sealed jar, without resorting to special appliances designed for that purpose. The reinforcement is designed to be united to the spun or pressed zinc cap of the usual form in such a manner that a unitary structure 15 is produced. I utilize the rigidity possessed by the unitary cap as a means whereby the removal of the cap from the sealed jar, no matter how firmly it may be seated thereon, may be easily effected. This result I achieve by 20 forming a transversely extending recess upon the cap, for the insertion of the blade of a case knife, or other instrument, which will permit a suitable leverage to be exerted upon the cap to effect rotation of the same 25 about the neck or mouth of the jar, either to tighten or loosen the cap.

In forming the said transverse recess for effecting the function described, I have in mind also its utilization as a convenient receptacle or holder for containing a label, upon which may be indicated the contents of the jar, and have so formed such recess that the label may be inserted or removed from the holder with facility.

30 In the foregoing, I have described in a general way the nature of my invention, and have also described the specific embodiment of certain features of the invention. In the matter which follows, I will make further 40 specific description of the structural features shown, and append to this specification the claims which define the novelty residing in my invention.

In the drawing which accompanies this 45 specification,

Figure 1 is a view in elevation showing the upper part of a Mason fruit jar of common and well-known type, and showing my improved cap structure in its preferred form 50 as applied thereto.

Fig. 2 is a plan view of the improved cap, showing the application of a lever thereto for the purpose of rotating the cap, and showing also in connection therewith a label 55 for indicating the contents of the jar.

Fig. 3 is a vertical sectional view through the central line of the cap, the view being taken on the line 3—3, Fig. 2.

In the drawing, the numeral 10 indicates 60 the upper part of a Mason fruit jar of well known commercial form, the jar being provided with integrally formed screw threads upon the neck thereof, as usual. A zinc cap of customary formation is indicated at 11, 65 and 12 is the usual gasket compressed be-

tween the shoulder of the jar and the flange of the cap when rotative pressure is applied to the latter. The usual vitreous lining for the cap is omitted, and with it its function of resisting the internal pressure upon the 70 inside surface of the top of the cap by the gases generated within the sealed jar.

The pliable nature of the metal used in forming the caps,—usually zinc,—necessitates the provision of some means in lieu of 75 the vitreous lining which will enable the cap to resist the expansive pressure referred to, in order that the top of the cap may be preserved in its planular condition and distortion thereof by bulging prevented. To 80 attain this end, I place about the top of the cap and exteriorly thereof a reinforcement which is formed of metal possessing sufficient rigidity to enable it to resist the pressures referred to, and thus prevent the distortion of the top of the cap from the plane 85 formed at the time of manufacture.

In its preferred form, the said reinforcement is in the nature of an auxiliary cap 13, the flange of which is adapted to be crimped 90 about the bead 14 of the cap 11, so as to effect a permanent engagement between the two parts and produce a unitary structure, with the said parts effectively locked against relative movement. They, therefore, turn as 95 one part when the cap is applied to the jar or removed therefrom.

The provision of an exterior reinforcement for the cap, which enables me to dispense with the usual vitreous lining, and at 100 the same time preserve the planular condition of the cap against disturbance, also enables me to utilize in a most convenient manner the rigid characteristics of the reinforced cap in constructing the rotating means whereby the cap may be unscrewed 105 from the jar. In producing such rotating means, a rectangular or elongated transverse area of the cap is displaced from the plane of the cap 13 into a plane parallel thereto, by the dies of an ordinary stamping press, prior to crimping the cap 13 in its final position. In the stamping operation, the ends of the area 15, are severed from the cap in the plane thereof, so as to permit the displacement of the metal in such area, but the metal at the side lines of the area is not severed, so that a connection 16 between the sides of the displaced area and the cap 13 is preserved, to constitute an open-end channel 17 on the top of the cap, produced by the separation of the metal in the said area 15 from the plane of the cap 13.

If the cap be found to engage the sealed jar so firmly that it cannot be loosened by 115 turning with the hand, the blade 18 of a case knife, or other suitable implement, may be inserted in the channel 17 of the cap, and a leverage secured which, by a rotative movement about the axis of the jar, will be suf- 120 125 130

ficient to loosen the cap without difficulty, and bring about its removal from the jar, in a manner which will be understood.

In addition to the provision described for effecting rotation of the cap, I am also enabled to provide a convenient means for holding a label indicating the nature of the contents of the jar. This result I achieve by limiting the extent of the lateral displacement of a smaller portion of the area 15, causing such portion 19, to remain in a plane slightly below that of area 15, so as to form a secondary channel 20, into which an indicating card or label 21, may be slipped and retained by frictional engagement. From what has been previously stated, the manner of forming the secondary channel 20, will be clearly understood by those conversant with the manufacture of metal structures of this class, and it will be sufficient therefore, for the present purpose to state that the cutting and formation of the secondary channel result from operations similar to those performed in constructing the main channel 17.

In the construction described, the unitary cap structure is provided with a channel in the hard metal portion to be engaged by any suitable implement, as a knife, to effect rotation of the cap, the channel structure being formed by the lateral displacement of the metal from the plane of the cap. This feature of the construction is dominant in whatever form the invention may be embodied. The provision of the means for holding the indicating card or label is merely incidental and subordinate to the dominant feature, and may be omitted without impairing the effectiveness of the principle of the invention.

My invention has greatly simplified the cost of production of jar closures of the present type, and has enabled me to preserve the desirable features of those in common

use. At the same time I dispense with the use of the costly and frangible vitreous linings, the use of which has been in very many cases attended with unsatisfactory results as well as disappointment.

Having thus described my invention, what I claim and desire to secure by Letters Patent of the United States, is:—

1. A closure for jars comprising a soft metal screw cap having a circular bead at the top thereof, in combination with an auxiliary cap of relatively harder material crimped upon the said bead to unite the elements in one structure, the said auxiliary cap being provided with a transverse opening for the insertion of an implement by means of which rotation may be imparted to the combined elements. 55

2. A closure for jars comprising a soft metal screw cap having a circular bead at the top thereof, in combination with an auxiliary cap of relatively harder material crimped upon the said bead to form a unitary structure with the soft metal cap, the said auxiliary cap having an implement receiving channel transversely of the top 65 thereof, whereby the combined elements may be rotated as a unit.

3. A closure for jars comprising a soft metal screw cap having a circular bead at the top thereof, in combination with an auxiliary cap of relatively harder material crimped upon the said bead to form a unitary structure with the soft metal cap, the said auxiliary cap having an area of its top 75 surface displaced from the plane thereof to 80 form an opening for the entry of an implement whereby the unitary cap may be rotated.

In testimony whereof, I have signed my name at Milwaukee this 30th day of April, 85 1921.

J. W. FAY.
